Primary Examiner — Kevin K Rudzinski*Assistant Examiner* — Richard E Yenchesky(74) *Attorney, Agent, or Firm* — KIRTON McCONKIE;
Evan R. Witt(57) **CLAIM**

The ornamental design for a multipurpose cleaning kit, as shown and described.

DESCRIPTION

FIG. 1 is a top perspective view of a multipurpose cleaning kit showing my new design;

FIG. 2 is a bottom perspective view thereof;

FIG. 3 is rear elevational view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a top plan view thereof; and,

FIG. 9 is an exploded perspective view showing component parts of the multipurpose cleaning kit, including a large brush, a small brush, and a dustpan.
